AIR AND WATER COOLED WALL

Maxwell Alpern, Philadelphia, Pa., assignor to
American Engineering Company, Philadelphia,
Pa., a corporation of Pennsylvania

Application July 5, 1929. Serial No. 376,176

7 Claims. (Cl. 122—235)

This invention relates to furnace walls and more particularly to the construction of a cooled furnace wall.

An important object of the invention is the production of a construction permitting the use of both water and air cooling elements in the wall.

A still further object of the invention is the provision of a structure permitting the use of air in cooling the wall of a furnace and the use of the air heated in the cooling operation to support combustion in the furnace.

A further and more specific object of the invention is provision in a construction of this character of an arrangement permitting ready combination therewith of water-cooled tubes for further enhancing the cooling effect.

A further object of the invention is to provide a structure of this character which will permit the furnace wall, if so desired, to be constructed without brick-work, thus materially reducing the cost thereof.

A still further object of the invention is to produce an element for use in the construction of an air-cooled wall which will promote the cooling of the wall and the transfer of heat to the cooling air so that this air is conditioned for most efficient use in the furnace.

A still further object of the invention is the provision of a construction wherein the cooling may be extended for the entire length of the wall or for only a portion thereof as is found necessary or desirable.

These and other objects I accomplish by construction shown in the accompanying drawings, wherein:

Fig. 1 is a vertical sectional view through a furnace embodying my invention;

Fig. 2 is a section on line 2—2 of Fig. 1;

Fig. 3 is an enlarged vertical sectional view through a slightly modified construction, the insulating blocks between the water cooling pipes being removed;

Fig. 4 is a section on line 4—4 of Fig. 3;

Fig. 5 is a section on line 5—5 of Fig. 3;

Fig. 6 is a vertical sectional view through a boiler furnace illustrating a construction wherein the air cooling feature is extended through only the lower portion of the wall;

Fig. 7 is a section on line 7—7 of Fig. 6;

Fig. 8 is a section on line 8—8 of Fig. 6;

Fig. 9 is a section on line 9—9 of Fig. 6;

Fig. 10 is a vertical sectional view through a furnace of the type employing pulverized fuel illustrating the application of the cooling feature to the side walls thereof and the method of con-

ducting the heated air into the furnace for use as secondary air in supporting combustion;

Fig. 11 is a section on line 11—11 of Fig. 10;

Fig. 12 is a section on line 12—12 of Fig. 10;

Fig. 13 is an enlargement of the sectional view of Fig. 11;

Fig. 14 is a detailed sectional view illustrating a modified structure in which insulating blocks are provided for the water-cooling tubes adjacent the fire zone; and

Fig. 15 is a perspective view of one of the duct-forming boxes employed in the construction of the wall.

Referring now to the drawings, and more particularly to Figs. 1 and 2 thereof, the numeral 10 generally designates the side wall of a furnace which, in accordance with my invention, is formed with a series of vertical ducts 11, the lower ends of which communicate through a suitable header 12 with intake of the blower 13 supplying air to the wind box 14 of the furnace. These ducts at the lower portion of the furnace have arranged thereagainst downwardly and rearwardly inclining water tubes 16 the forward and rear ends of which communicate with headers 17 which may in turn communicate through suitable ducts with the headers or drums of the usual boiler tube apparatus generally designated at 18. Between the tubes 16 and against the face of the inner walls of ducts 11 I dispose a refractory cement protecting the inner duct walls against direct contact with the contents of the furnace as indicated at 19. In the majority of constructions those tubes adjacent the fuel bed are preferably protected by means of insulating blocks as indicated at 20a (see Fig. 14). The tubes 16 connecting headers 17 may either diverge rearwardly as shown in Fig. 1 or may be parallel as in Fig. 3.

The ducts 11 are open at their upper ends and it will, of course, be obvious that during operation of blower 13 the current of air will be drawn through these ducts thereby cooling the wall. This air in cooling the wall becomes heated and is accordingly conditioned for efficient use in the wind box of the furnace. This air, in the present instance, is illustrated as supplying all the air employed in supporting combustion in the furnace but may, as hereinafter more fully described, furnish only a portion thereof.

The preferred construction for the wall is more clearly shown in Figs. 3 to 5 inclusive and in the detailed showing of Fig. 15. In this construction, as more clearly shown in Fig. 5, the elements employed in the formation of the duct include

boxes 20, partitioning and spacing elements 21 and 21a and paneling generally designated at 22. The boxes each comprise a main plate 23 having outstanding flanges 24 at its sides and having its ends formed with slots 25 for the reception of cement by means of which the end edges of adjacent boxes are sealed to one another. The inner faces of the plate between the flange are provided with short inwardly directed longitudinally extending ribs 26 which, as more clearly shown in Fig. 15, are preferably each formed from a plurality of sections 27, the sections of adjacent ribs being staggered with relation to one another. The flanges 24 are perforated as at 27a for the passage of securing elements 28 for engagement in the partition plates 21, which partition plates are continuous for the length of the duct and have arranged between the free edges thereof the removable panels of insulating material 22. Partitioning elements 21 may be employed in mounting securing elements for the paneling as designated at 29 in Fig. 5. The partitioning elements 21a may be omitted as suggested in Fig. 13 and there may be any desired number of rows of boxes between adjacent partitioning elements as will be obvious by a comparison of Figs. 5 and 12.

In some instances it proves advisable or necessary to terminate the air ducts below the upper end of the side wall of the furnace and in such instances I provide a horizontally extending duct 30 and more clearly shown in Figs. 7 to 9 inclusive. This duct has one end thereof open as at 31 and is preferably supplied with air from a blower through a conduit generally designated at 32. The duct decreases in size toward its closed end being at present illustrated as decreasing both in width and depth and the decrease in size as beginning at the point of connection with the upper ends of the cooling ducts 11. The lower ends of the cooling ducts 11 open to the ordinary wind box space 14. It will be noted that in each of the instances hereinbefore set forth the air passing through the ducts is delivered to the wind box, this delivery being accomplished through a fan which may either deliver air to the cooling ducts or withdraw air from these ducts for delivery to the box. It will also be noted that the cooling ducts need not extend for the full depth of the side wall and may, in fact, terminate so that each of these ducts can communicate at its lower end with the space beneath the grates.

A structure of the character just described is advantageous in many instances where cooling of the wall above the lowermost of the normal boiler tubes is unnecessary. The wall above the wind box 30 may be made of any usual or preferred construction.

In Figs. 10 to 13 inclusive I have illustrated a modification of the structure to permit its incorporation in a furnace employing pulverized fuel. In this construction the cooling ducts 11 are blower-fed and extend horizontally in the side walls of the furnace. The rear wall of the furnace designated at 33 is provided with ducts 34 connecting with the cooling ducts 11 and having their inner walls pierced at intervals as indicated at 35 to permit the air to pass into the furnace and thus provide secondary air to support combustion therein. It will be seen that at each instance the ducts 11 serve to provide at least a portion of the air supporting combustion in the furnace so that the ducts act not only in cooling the wall but likewise as a means for preheating air for this purpose.

The arrangement of the tubes in rearwardly

divergent relation as shown in Fig. 6 permits the water-cooled tubes to cover the boiler wall space below the boiler tubes without being disposed in overlapping relation to these tubes as in Fig. 3. It will be obvious that with a construction such as shown in Fig. 3 if the cooling tubes cover the entire boiler wall surface below the boiler tubes there will be a substantial overlap of the boiler and water-cooling tubes. This overlap is, in practically all instances, unnecessary and accordingly this rearward divergence permits of the production of a more efficient and at the same time a cheaper construction.

Since the arrangement of the ducts must obviously be varied in order to permit accommodation of the construction to a given boiler construction, I do not wish to be understood as limiting myself to the specific arrangements herein illustrated except as hereinafter claimed.

I claim:

1. A furnace wall comprising an inner metallic shell in an outer panel structure of insulating material, means supporting said panel structure from and in spaced relation to said metallic shell and combined with the panel structure and shell to produce parallel ducts for the passage of cooling air, the metallic shell having inwardly projecting vanes disposed in said ducts and said vanes being relatively short in the dimension longitudinally of the ducts and arranged transversely in staggered relation.

2. A furnace wall comprising at least in part an inner facing consisting of a plurality of metallic boxes arranged in side to side relation and each comprising a plate having inwardly projecting vanes arranged in staggered relation, an outer wall facing consisting of insulating panels and means supporting said panels from and in spaced relation to said boxes and subdividing the space between the facings into a plurality of parallel ducts.

3. A furnace wall comprising at least in part an inner facing consisting of a plurality of metallic boxes arranged in side to side relation and each comprising a plate having inwardly projecting vanes arranged in staggered relation, an outer wall facing consisting of insulating panels and means supporting said facings in spaced relation subdividing the space therebetween into a plurality of parallel ducts, said plates having flanges at their side edges, said supporting means extending between the flanges of adjacent boxes and being secured thereto.

4. In a furnace, the combination with front and rear walls, of a side wall, a bank of boiler tubes inclined between the front and rear walls, headers arranged at the front and rear ends of said side wall, and water-cooled tubes connecting said headers and disposed against the inner face of said side wall and being inclined oppositely to the boiler tubes, the header at the upper end of said water-cooled tubes being shorter than the other, and said tubes diverging toward the longer header whereby the said water-cooled tubes are made to embrace a relatively large section of the side wall without materially overlapping the lower ends of said boiler tubes.

5. A furnace wall comprising an inner metallic section, an insulated outer section in spaced relation to said inner section, and a series of water-cooled tubes disposed in contact with said inner wall section, said series of tubes being inclined to the horizontal and diverging towards one end whereby the said series embraces at the

latter end a greater area of the wall surface than at the other end.

6. In a furnace, the combination of a combustion chamber, walls defining said chamber, said walls comprising a series of substantially vertical ducts having air inlets at the upper ends thereof, the inner side of said ducts being comprised of a series of metallic box members, a series of fluid conducting tubes lying in close juxtaposition to the inner side of said ducts and inclining downwardly from front to rear of said chamber, a stoker, a pressure chamber beneath said stoker, and means for drawing air into said ducts and discharging it into said pressure chamber, said air being heated as it passes through said ducts.

7. In a furnace, the combination of a combustion chamber, walls defining said chamber, said walls comprising a series of substantially vertical ducts having air inlets at one end thereof, a series of fluid conducting tubes adjacent said ducts and inclining downwardly from front to rear of said chamber, said tubes diverging toward the rear of said chamber so as to cover a greater area of said walls, a stoker, a pressure chamber beneath said stoker, and means for drawing air into said ducts and discharging it into said pressure chamber, whereby said air both cools said walls and enters the combustion chamber in a highly preheated state.
